DESIGN FOR A CARD CONTAINER

Joseph M. Gross, Los Angeles, Calif., assignor to
West Coast Sales Incorporated, Los Angeles,
Calif., a corporation of California

Application July 2, 1941, Serial No. 101,855

Term of patent 3½ years

To all whom it may concern:

Be it known that I, Joseph M. Gross, a citizen of the United States, and a resident of the city of Los Angeles, in the county of Los Angeles and State of California, have invented a new, original, and ornamental Design for a Card Container, of which the following is a specification, reference being had to the accompanying drawing, forming part thereof.

In the drawing:

Figure 1 is a perspective view of a card container embodying my new design.

Figure 2 shows an end elevational view of same, this view being shown on a larger scale than Fig. 1.

The end of the card container not shown is the same as that shown in Figs. 1 and 2 of the drawing.

I claim:

The ornamental design for a card container, substantially as shown and described.

JOSEPH M. GROSS.
